UNITED STATES PATENT OFFICE.

WASHINGTON M. POTTER, OF FREEDOM, PENNSYLVANIA.

LUNCH KIT.

1,380,019.

Specification of Letters Patent. Patented May 31, 1921.

Application filed September 1, 1920. Serial No. 407,437.

To all whom it may concern:

Be it known that I, WASHINGTON M. POTTER, a citizen of the United States, residing at Freedom, in the county of Beaver and State of Pennsylvania, have invented certain new and useful Improvements in Lunch Kits, of which the following is a specification, reference being had to the accompanying drawings.

10 This invention relates to certain improvements in lunch kits, and it is an object of the invention to provide a novel and improved device of this general character which, when in one adjustment, serves as a 15 container or receptacle to carry food stuffs or the like, and, when in a second position, affords a table upon which the food may be arranged.

An additional object of the invention is 20 to provide a novel and improved device of this general character which is especially designed and adapted for use in connection with an automobile and wherein the same normally provides a container occupying a 25 small amount of space whereby the same may be conveniently carried by the automobile and which is also capable of being extended to provide a table.

Another object of the invention is to provide a novel and improved device of this 30 general character which primarily comprises a collapsible box or receptacle which, when extended, serves as a table and wherein means are provided to conveniently and effectively maintain the table in a proper position.

Furthermore, it is an object of the invention to provide a device of this general character which, when employed as a table, is 40 provided with means adapted to coact with the vehicle structure to support and maintain the same in desired position.

It is also an object of the invention to provide a novel and improved device of this 45 general character which, when employed as a table, is provided with means adapted for coaction with a portion of the vehicle structure, together with additional means affording a supporting leg adapted to rest upon 50 the floor of the vehicle and wherein such supporting leg, when the device is folded

or adjusted for use as a box or container, is housed within said box or container.

The invention consists in the details of construction and in the combination and arrangement of the several parts of my improved lunch kit whereby certain important advantages are attained and the device rendered simpler, less expensive and otherwise more convenient and advantageous for use, 60 as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in perspective, with a portion broken away, of a kit constructed in accordance with an embodiment of my invention and arranged in a position to be used as a receptacle or container. 70

Fig. 2 is an enlarged vertical sectional view taken longitudinally through the device as illustrated in Fig. 1. 75

Fig. 3 is a transverse vertical sectional view taken substantially on the line 3—3 of Fig. 2.

Fig. 4 is a vertical sectional view taken through the device when employed as a 80 table, the coacting and adjacent portions of an automobile being diagrammatically indicated by dotted lines.

Fig. 5 is a view in perspective of the device when used as a table with a portion 85 broken away, the coacting portion of an automobile being also diagrammatically indicated by dotted lines, and

Fig. 6 is a detail sectional view taken substantially on the line 6—6 of Fig. 5. 90

As disclosed in the accompanying drawings, my improved device comprises an elongated bottom panel or section 1 preferably oblong in form and hingedly connected with the longitudinal margins thereof 95 and preferably by a fabric hinge 2 are the side walls or panels 3 of desired dimensions.

4 denotes an end member or panel having its bottom and side marginal portions defined by the inwardly disposed flanges 5 100 which overlie the outer faces of the bottom member or panel 1 and the side members or

panels 3 when in folded relation. The bottom flange 5 is provided with one or more upstanding pins 6 which seat within a recess or socket 7 produced in the under or outer 5 face of the bottom member or panel 1 when the end panel or member 4 is in applied position.

Extending along the upper edge of the end member or panel 4 is a strip 8 of a 10 width sufficient, when in one position, to overlie the top panel or member 9 to be hereinafter more particularly referred to. Each end of the strip 8 is provided with an inwardly directed web or flange 10 pivotally 15 engaged, as at 11, with an upper or outer corner portion of a side member or panel 3, so that the strip 8 may be readily swung to facilitate the removal of the end member or panel 4 or to facilitate the maintenance 20 thereof in applied position.

The top panel 9 snugly fits between the upper marginal portions of the side members or panels 3 and is provided at each end portion with the outwardly and laterally directed pins 12 which seat within the openings 14 produced in the side members or panels 3 so that when the kit is in folded or compacted adjustment, as illustrated in Fig. 1, the device in its entirety may be readily 25 transported through the medium of a hand grasp 15 suitably engaged with the central portion of the top member or panel 9.

Extending along the outer or upper longitudinal margin of each of the side members or panels 3 is a strip 16 of a width to overlie the adjacent longitudinal marginal portion of the applied top member or panel 9 to further facilitate the securing of said top member or panel in such position. The 30 opposite end portions of the strips 16 are provided with inwardly directed flanges 17, each of which is pivotally engaged, as at 18, with an end edge portion of the top member or panel 9 and whereby the strip 16 may be 35 readily swung into either an operative or inoperative position. The end section or panel 4 is entirely removable.

19 denotes a second end panel which has its side and bottom marginal portions defined by the outstanding flanges 20 which 40 overlie the outer faces of the bottom panel or member 1 and the side panels or members 3 when the device is folded and the bottom flange 20 is hingedly connected, as at 45 21, so that said panel or member 19 may be swung downwardly below the bottom member or panel 1, as indicated in Figs. 4 and 5 of the drawings.

The opposite end portion of the member 60 or panel 19 has extending therealong the strip 22 of a width to overlie the adjacent end portion of the top panel or member 9 when the device is in its folded or compacted adjustment, and each end portion of said 65 strip 22 is provided with an inwardly dis-

posed flange 23 pivotally engaged, as at 24, with the adjacent side portion of the member or panel 19. Each of the strips 8 and 22 at substantially its longitudinal center is provided with an upstanding lug 25 with 70 which coacts a pivoted hasp 26 carried by the adjacent portion of the top member or panel 9 and whereby the end members or panels 4 and 19 are effectively locked in applied position when the device is folded 75 or compacted for use as a receptacle.

The top or upper face of the bottom member or panel 1 at the end portion thereof with which coacts the end member or panel 4 is provided with a transversely disposed 80 groove or recess 27 spaced slightly inwardly of the adjacent end of the member or panel 1 and said face of the panel or member 1 is provided with the longitudinally disposed open channels 28 in communication with 85 the groove or recess 27. Slidably engaged within the channels 28 are the side members 29 of a substantially U-shaped member A, the intermediate portion 30 of said member A being arranged within the groove or 90 recess 27. The groove or recess 27 is of a width to permit the requisite sliding movement of the member A lengthwise of the side members 29 thereof. The outer end portion of each of the side members 29 terminates in a depending lug or finger 31 which, when the member A is at the limit of its inward movement, is housed within a recess or notch 32 provided in the adjacent end portion of the member or panel 1. The 95 member A is maintained in applied position by the plate 33 suitably secured to the upper face of the member or panel 1 and overlying the groove or recess 27 and channels 28.

When my improved device is to be used as 100 a table, each of the lugs or fingers 31 is disposed through a bracket 34 extending rearwardly from the central portion of the back of the front seat 8 of an automobile or other supporting structure, such engagement being 105 effected after the end member or panel 4 has been removed and the upper end projected sufficiently. The end member or panel 19 is then swung downwardly to the position illustrated in Figs. 4 and 5 and the 110 legs L caused to rest upon the floor of the vehicle or the like. The legs L are adapted to move longitudinally of the member or panel 19 and have their inner end portions hingedly connected, as at 35, whereby they 115 are capable of relative swinging movement. Each of the legs L is provided with a longitudinally directed slot 36 through which is disposed a headed shank 37 carried by a swinging arm 38. The arms 38 are two 120 in number and have their inner ends in overlapping relation and pivotally engaged as at 39, with the inner face of the member or panel 19 adjacent the free end thereof. The arms 38 permit the legs L to be moved 125

inwardly of the member or panel 19 so that when the device is folded or compacted for use as a container or receptacle, said legs L are housed therein.

- 5 As the legs L are moved outwardly and downwardly with respect to the member or panel 19 to engage the floor of the vehicle or the like, the arms 38 cause said legs L to separate and the free end portions of said 10 arms, when the legs are at the limit of their separating movement, pass under the clips 40 carried by the adjacent face of the member or panel 19, whereby said arms 38, together with the legs L, are held against 15 movement away from the member or panel 19.

When the legs L are extended, they are held against return or retrograde movement by the flat spring 41 having one end 20 anchored, as at 42, within a groove or channel 43 produced in the inner face of the member or panel 19. The opposite end portion of the spring is provided with the bill 44 for contact with the hingedly connected, 25 ends of the legs L when extended, so that said legs L are held against return movement.

Each of the side panels or members 3 has pivotally engaged, as at 45, with the opposite end portions thereof the elongated cleats 46 of a length when arranged in parallelism with the ends of the member or panel 3 to extend beyond the outer or free longitudinal marginal portion thereof a distance sufficient to overlie the upper edges of the side walls W of an automobile. When the device is compacted or folded, the cleats 46 extend longitudinally of the member or panel 3 but the outward swinging movement 40 of each of said cleats 46 is limited by contact with a finger or plate 47 carried by the adjacent end of the member or panel 3 and extending inwardly thereof. The free end portion of said finger or plate 47 terminates 45 in an inwardly disposed flange 48 beneath which extends the cleat 46 whereby the member or panel 3 is held against downward swinging movement when the device is arranged within the automobile for use as a 50 table.

My improved kit also includes two boards or panels 49. Each of the boards or panels 49 is of a length coextensive with the length of a member or panel 3. Each of the boards or panels 49 is of such width to cause the outer marginal portion thereof to rest upon the upper edge of a side wall of the automobile when said board or panel is positioned adjacent the outer margin of a member or panel 3. When so positioned, the end portions of the member or panel 49 underlie the outer end portions of the extended cleats 46 and each end portion of the board or panel 49 is provided with a strip or plate 50 extending beyond the inner margin thereof

and which overlies the adjacent marginal portion of the member or panel 3 whereby said board or panel 49 is effectively maintained in applied position.

When the device is compacted or folded, 70 a board or panel 49 is rested upon a pair of folded cleats 46 with the extended portions of the plates 50 overlying one of said cleats while each end portion of the board or panel adjacent its top underlies an inwardly directed flange 48 hereinbefore referred to and as is particularly illustrated in Figs. 2 and 3.

A lunch kit constructed in accordance with my invention can be readily compacted or folded for use as a receptacle or container or extended for use as a table. When arranged for use as a receptacle or container, the parts housed therein occupy but very little space so that it is possible to pack within the receptacle or container a relatively large amount of food, together with analogous articles.

From the foregoing description it is thought to be obvious that a lunch kit constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A kit of the class described comprising a bottom panel, side panels hingedly connected thereto, end panels coacting therewith when the side panels are folded, a removable top panel, and a supporting member slidably supported by an end portion of the bottom panel and movable longitudinally thereof, said bottom panel being provided with means coacting with the supporting member for limiting the movement of said supporting member, said supporting member when in one position extending beyond the adjacent end of the bottom panel.

2. A lunch kit comprising a bottom panel, side panels hingedly connected thereto, an end panel hingedly connected with the bottom panel, a second end panel, and a top panel adapted to be positioned between the end panels, said top panel and side panels being provided with coacting locking means, said top panel and end panels being also provided with coacting locking means, said hinged end panel providing a supporting means when the side panels are extended, the opposite end portion of the bottom panel being provided with additional supporting means.

3. A lunch kit comprising a bottom panel, side panels hingedly connected thereto, an end panel hingedly connected with the bottom panel, a second end panel, a top panel adapted to be positioned between the end panels, said top panel and side panels being provided with coacting locking means, said top panel and end panels being also provided with coacting locking means, and a leg slidably supported by the hinged end panel and movable beyond the free end thereof when said end panel is in open position, said leg overlying the inner face of said hinged end panel when said panel is in closed position.
4. A lunch kit comprising a bottom panel, side panels hingedly connected thereto, an end panel hingedly connected with the bottom panel, a second end panel, a top panel adapted to be positioned between the end panels, said top panel and side panels being provided with coacting locking means, said top panel and end panels being also provided with coacting locking means, a leg slidably supported by the hinged end panel and movable beyond the free end thereof when said end panel is in open position, said leg overlying the inner face of said hinged end panel when said panel is in closed position, and means for holding said leg against movement inwardly of the end panel when extended.
5. A lunch kit comprising a bottom panel, side panels hingedly connected thereto, an end panel hingedly connected with the bottom panel, a second end panel, a top panel adapted to be positioned between the end panels, said top panel and side panels being provided with coacting locking means, said top panel and end panels being also provided with coacting locking means, a leg slidably supported by the hinged end panel and movable beyond the free end thereof when said end panel is in open position, said leg overlying the inner face of said hinged end panel when said panel is in closed position, and means for limiting the outward movement of the leg relative to the end panel.
6. A lunch kit comprising a bottom panel, side panels hingedly connected thereto, an end panel hingedly connected with the bottom panel, a second end panel, a top panel adapted to be positioned between the end panels, said top panel and side panels being provided with coacting locking means, said top panel and end panels being also provided with coacting locking means, a pair of legs carried by the hinged end panel, said legs having adjacent ends hingedly connected, each of said legs being provided with a longitudinally disposed slot, and a headed member extending through the slot of each of the legs and carried by the end panel.
7. A lunch kit comprising a bottom panel, side panels hingedly connected thereto, an end panel hingedly connected with the bottom panel, a second end panel, a top panel adapted to be positioned between the end panels, said top panel and side panels being provided with coacting locking means, said top panel and end panels being also provided with coacting locking means, a pair of legs carried by the hinged end panel, said legs having adjacent ends hingedly connected, each of said legs being provided with a longitudinally disposed slot, plates pivotally engaged with the end panel, and a headed member carried by each of the plates and extending through the slot of the leg.
8. A lunch kit comprising a bottom panel, side panels hingedly connected thereto, an end panel hingedly connected with the bottom panel, a second end panel, a top panel adapted to be positioned between the end panels, said top panel and side panels being provided with coacting locking means, said top panel and end panels being also provided with coacting locking means, a pair of legs carried by the hinged end panel, said legs having adjacent ends hingedly connected, each of said legs being provided with a longitudinally disposed slot, plates pivotally engaged with the end panel, a headed member carried by each of the plates and extending through the slot of the leg, and clips carried by the end panel and beneath which the plates engage when the legs are in a position to extend beyond the free end of the end panel.
9. A lunch kit comprising a bottom panel, side panels hingedly connected thereto, an end panel hingedly connected with the bottom panel, a second end panel, a top panel adapted to be positioned between the end panels, said top panel and side panels being provided with coacting locking means, said top panel and end panels being also provided with coacting locking means, cleats pivotally engaged with the side panels and adapted to extend beyond the outer edges thereof when said side panels are extended, and supplemental panels provided with means engageable with the side panels.
10. A lunch kit comprising a bottom panel, side panels hingedly connected thereto, an end panel hingedly connected with the bottom panel, a second end panel, a top panel adapted to be positioned between the end panels, said top panel and side panels being provided with coacting locking means, said top panel and end panels being also provided with coacting locking means, cleats pivotally engaged with the side panels and adapted to extend beyond the outer edges thereof when said side panels are extended, supplemental panels provided with means engageable with the side panels, and means

carried by the side panels for limiting the outward movement of the cleats.

11. A kit of the class described comprising a bottom panel, side panels hingedly connected thereto, end panels coacting therewith when the side panels are folded, a removable top panel, and a supporting

member supported by an end portion of the bottom panel for sliding movement in a direction longitudinally of the bottom panel 10 and adapted to extend therebeyond.

In testimony whereof I hereunto affix my signature.

WASHINGTON M. POTTER.
